UNITED STATES PATENT OFFICE.

HYMAN BRESLAVSKY, OF NEW YORK, N. Y.

DESIGN FOR A SETTING FOR PRECIOUS STONES.

58,305.

Specification for Design.

Patented July 12, 1921.

Application filed July 1, 1920. Serial No. 393,442. Term of patent 3½ years.

To all whom it may concern:

Be it known that I, HYMAN BRESLAVSKY, a citizen of the United States, residing at New York, borough of Manhattan, in the county and State of New York, have invented a new, original, and ornamental Design for Settings for Precious Stones, of which the following is a specification, reference being had to the accompanying drawing, forming part thereof.

Figure 1 is a top plan view of a setting for precious stones.

Fig. 2 is a side view of the same.

The design resides in prongs cut and arranged to constitute a six pointed star when bent to a position to hold the stone, with smaller stone receiving openings for the reception of smaller stones, said openings being singly disposed within the confines of each prong.

I claim:

The ornamental design for a setting for precious stones substantially as shown.

HYMAN BRESLAVSKY.
